United States Patent Office.

JOSEPH PERRAULT, OF TROY, NEW YORK.

Letters Patent No. 102,964, dated May 10, 1870.

IMPROVEMENT IN PRESSURE BLOWERS.

The Schedule referred to in these Letters Patent and making part of the same.

To all whom it may concern:

Be it known that I, JOSEPH PERRAULT, of Troy, in the county of Rensselaer and State of New York, have invented certain new and useful Improvements in Pressure Blowers; and I do hereby declare the following to be a full, clear, and exact description thereof, reference being had to the accompanying drawings of the same, which make part of this specification, and in which—

Figure 1 represents an elevation of a pressure-blower embracing my improvements.

Figure 2 represents a vertical section of the same taken through the air-wheel.

Figure 3 represents a vertical axial section.

Figure 4 represents an inside elevation with the wheel removed.

Figure 5, a view in perspective of one of the buckets detached from the wheel.

My invention relates to pressure or fan-blowers for furnaces, forges, and other purposes, and consists in constructing the fan-case with an interior shell in such manner as to form air-chambers on each side of the wheel between the inner shell and the outer case, and an inclosing case for the buckets of the wheel, for the purpose of protecting the fan, while in motion, as far as possible, from friction caused by the back pressure of the air; also, in the peculiar construction of the buckets of the wheel; also, in the employment of a register for regulating the blast while the fan is in motion, and without changing the speed of the engine or machinery conveying power and motion to the fan.

In the accompanying drawings—

A represents the circular case within which the fan-blower is supported and revolves. This case has a contracted neck, A', at its center, leaving only sufficient space for the reception of the hub and spider of the air-wheel, but is enlarged around its circumference, and made with a double-arched shell, so as to form three annular chambers; a middle one within which the buckets of the wheel are fitted and revolve, and an air-chamber, B, on either side thereof, intervening between the inner shell C, and the inclosing case A. At the contracted neck A', the hubs D are cast with, and project from the case and form bearings for the shaft of the fan-wheel. A series of holes, a, is made in each side of the arched case A, communicating with the air-chamber B therein, and these holes are provided with a register, E, having holes b corresponding with those in the case. The register is a circular plate fitted within a seat in the side of the case, and having slots c in it through which screw-bolts d pass to secure it to the case, and allow it to be adjusted to increase or diminish the area of the openings of the air-chambers, to regulate the blast without changing the speed of the engine.

The inner arched shells C extend from the inner side of the outer case toward the center of the wheel, a distance sufficient to cover the ingress air-openings a, and leave openings f between them and the contracted neck of the case, for the passage of the air to the wheel.

The inner arched shells thus arranged form the two side annular air-chambers B, a central air-pressure chamber F, and an interior inclosing case for the wheel. This inclosing case, C, is formed by two concentric flanges or plates G, extending from near the middle of the depth of the arched shells in an angular direction toward the crown of the arch, so as to form a roof to the sides of the wheel, leaving an opening between them equal in area to the exit openings of the buckets. This angular inclosing roof protects the wheel from back pressure, and relieves it while in motion from the friction of the air under pressure.

The edges of the projecting annular plates G, fit against each side of the circumference of the wheel, and the arched shells C are provided with annular rings, g, surrounding the inlet-passages f, from the air-chambers B, which fit in close proximity to corresponding rings h on the sides of the fan-wheel, thus shutting off all communication between the air supplied to the fan and the air forced from it, thus increasing the insulation of the wheel from the air-pressure chamber F, which is located between the roof of the wheel and the arch of the inner shell, but has no communication with the air-chamber except through the buckets of the wheel.

The fan or air-wheel is secured to its driving-shaft H, by means of a spider, I, to the radial arms of which are attached cross-arms, J, which support the annular rings h, and the buckets.

The air-wheel is provided with a suitable number of buckets, K, made of sheet metal, with their sides inclined outward, and fitting closely the inner sides of the shells and the obliquely projecting roofs, while their other sides are curved in a direction opposite to that of the motion of the wheel. The ingress openings i of these buckets are equal to the space between the arched shells, and are, therefore, oblong in the direction of the axis of the wheel; while their exit-openings j, are only equal in width to the space between the projecting edges of the oblique roofs of the wheel, and are of a length in the direction of the motion of the wheel equal to that of their axial length; and the areas of the inlet and discharge-openings i, j, are equal, or nearly so, so that the air will pass out of the bucket as freely as it enters it, into the encircling pressure air-chamber F, from whence it escapes through the tangential opening L, in the case, to the furnace.

The step or pulley-frame M, is secured, by means of a set-screw, directly to one of the projecting hubs D

of the case, so that it may be turned in any position desired on the end of the shaft, and in the outer end of this step-frame is placed a metal composition thimble, *e*, bored with a tapering socket into which is fitted the correspondingly-shaped end of the driving-shaft *H*, so as to take up the wear of the bearing by a set-screw, *m*, and form a lateral support to the shaft.

The fan thus constructed is compact, simple, durable, and, being revolved within a sealed chamber, secures the greatest possible pressure of the air within the supply-chamber, while the wheel is entirely protected from back pressure. Moreover, it will be seen, as the wheel revolves, the convex sides of the buckets, (instead of their concave sides, as heretofore,) being presented to the air, they force it from the wheel like a wedge, with a rolling motion, throwing it tangentially from the curve into the air-chamber *F*, and therefore consuming less power, and sustaining more pressure than a radial, or concave blade could do, because, if the fan were revolved with the straight or concave sides of its buckets to the air, it would whirl the latter round with it instead of throwing it off tangentially.

Having thus described my invention, I claim—

1. The case *A*, constructed with a central closed neck, *A'*, for inclosing the hub of the wheel, and an enlarged arched circumference for inclosing the buckets of the wheel, substantially as hereinbefore described.
2. The central closed neck *A'* of the case, made with projecting hubs *D*, for the support and bearings of the central driving-shaft *H*, and attachments for the pulley-frames, as herein shown and described.
3. The arched case *A*, constructed with air-inlet openings *a b*, near its circumference, in combination with air-supplying chambers *B*, arranged contiguous thereto, and communicating with the buckets of the air-wheel, substantially as hereinbefore described.
4. The inlet air-openings *a* of the case *A*, provided with a circular register *E*, for regulating the blast of the fan without changing the speed of the engine, as herein shown and described.

5. The arched case *A*, constructed with an interior encircling air-pressure chamber, *F*, in combination with the intermediate air-supplying chambers *B*, substantially as hereinbefore described.

6. The arched shells of the case *A*, constructed with obliquely-projecting flanges or plates, *G*, which serve as an inclosing roof to the wheel, for the purpose of relieving it from the friction of the back pressure of the air, substantially as hereinbefore described and shown.

7. The air-wheel, constructed with buckets *K*, having the greatest length of their ingress-openings parallel with the axis of the wheel, and that of their egress-openings in the direction of the motion of the wheel, and the two of equal area, or nearly so, substantially as hereinbefore described.

8. The acting sides of the buckets of the fan-wheel, curved in a direction opposite to that of the motion of the wheel, in combination with egress openings, having their greatest length in the direction of the motion of the wheel, and their ingress-openings, having their greatest length in an axial direction, substantially as hereinbefore described.

9. The annular rings *g*, surrounding the inlet-openings of the arched shells *C*, in combination with the annular rings *h* on the sides of the buckets, and the oblique-projecting roofs *G*, for the purpose of shutting off all communication between the air supplied to the fan and that forced from it, substantially as hereinbefore described.

10. The combination of the arched inclosing case *A*, the intermediate air-supplying chambers *B*, the arched shells *C*, having annular obliquely-projecting roofs *G*, with the air-wheel, constructed with buckets as described, and the inclosing central air-pressure chamber *F*, the whole constructed, arranged, and operating as hereinbefore described.

JOSEPH PERRAULT.
